UNITED STATES PATENT OFFICE.

JAY G. SWAB, OF BALDWIN, NEW YORK, ASSIGNOR TO TENSION ENVELOPE CO. INC., OF NEW YORK, N. Y., A CORPORATION OF NEW YORK.

METHOD OF MAKING ENVELOPES.

Application filed June 30, 1926. Serial No. 119,658.

My invention relates to a novel method of making envelopes of the type in which a fastener is applied to the body of the envelope to co-operate with an aperture or eyelet applied to the flap of the envelope. It is common practice to make envelopes adapted to be sent through the mails unsealed, with a metal fastener attached to the body of the envelope at the back wall near the flap end, and these fasteners have consisted of several types, one of which comprises an eyelet portion which is riveted through the wall of the envelope and on the exterior there are oppositely projecting lugs or fingers which are adapted to be bent upwardly to pass through the aperture or eyelet in the flap and afterwards bent down on the outer surface of the flap to secure the latter in folded position against the back wall of the envelope. As stated above, various other types of metal fasteners have been used, and while I prefer to illustrate my invention in connection with the particular form here described, it will be understood that the method may be adopted in the making of envelopes having other forms of fasteners. It has been common practice, also, to provide an aperture in the flap as above set forth, to receive the prongs of the fastener, and the flap is usually reinforced by applying patches or discs of paper or cardboard to the flap around the aperture.

The method employed for many years in the making of such envelopes has resulted in considerable waste due to rejections on account of the fold or crease of the flap being improperly positioned, so that when the flap was folded upon the rear wall of the envelope, the eyelet of the flap did not accurately register with the metal fastener. Not only have there been material losses caused by rejections, but in the manufacture of these envelopes it has been necessary to inspect them in order, as far as possible, to eliminate such envelopes as were not accurately made. In this former method of manufacture, the envelope was first formed to comprise the body portion and the flap projecting from one end thereof, and at the same time the crease was formed on the line on which the flap was intended to be folded. All of this was done on the envelope machine. After the envelope was thus made

with the crease line formed, it was applied to the machine which attached the metal fastener and formed the reinforced aperture in the flap. If, after these parts were attached to the envelope and flap, the crease line happened to come exactly midway between the center of the metal fastener and the eyelet, the flap could be folded over, and the eyelet would register properly with the metal fastener. In many cases, however, this crease which was previously formed was not accurately positioned, i. e., it was either not midway between the center of the fastener and the eyelet, or it was slightly diagonal in relation to the flap, and in such cases it was necessary to cull out the envelopes inaccurately made, if inspection disclosed any error, or else such envelopes were likely to be rejected by the customers of the manufacturer.

Under my present method I am able to avoid the necessity for inspection and to entirely avoid rejections due to the inaccuracies above referred to. This is accomplished broadly by forming the crease or fold for the flap simultaneously with the attachment of the fastener to the envelope and the formation of the eyelet. As the fastener and eyelet are attached simultaneously by mechanical means, the distance between the center of the fastener and the center of the eyelet is always uniform on any given size envelope and under my method the crease or fold is preferably formed simultaneously with the application of the fastener and the formation of the eyelet, so that the crease will always be formed exactly midway between the two centers. As a result, when the flap is folded on the crease line, the eyelet and the fastener will always register. This is true even though the crease line is not exactly at right angles with the side edges of the envelope.

While various mechanisms may be used for carrying out my improved method, I have illustrated in the accompanying drawings parts of an ordinary known machine for applying fasteners to envelopes, wherein I have applied certain additional mechanism for carrying out the present method.

In the drawings forming part of this application,

Figure 1 is a front elevation of portions

of an envelope fastener applying machine embodying the parts necessary to carry out my process.

Figure 2 is a plan view of the parts shown in Figure 1,

Figure 3 is a rear elevation of an envelope prepared for receiving the fastener and eyelet in accordance with my invention,

Figure 4 is a similar view of the envelope after the same has been treated according to the present process, and Fig. 5 is a detail view of one of the end frame members of my machine.

In Figure 3 I have shown a common type of envelope to which fasteners are usually applied. In this view the rear wall 2 of the envelope 1 is shown, the overlapping edges 3 of this wall being glued or pasted together to extend lengthwise of the envelope and the lower end 4 is folded over and secured against the rear wall. At the opposite end of the envelope the front wall 6 is carried forward to form a flap 5 which projects beyond the end 7 of the rear wall sufficiently to permit the flap to be folded over and to overlap one end of the back wall 2. Under the present process the envelope, as shown in Figure 3, remains uncreased at the base of the flap as it comes from the envelope machine, whereas in present practice there is usually a crease formed across the base of the flap and adjacent the corners 8 where the upper edge 7 of the back wall of the envelope merges with the base of the flap. In Figure 4 I have shown an envelope which has been completed according to my present method. In this view the envelope differs from that of Figure 3 in the fact that the fastener 9 which consists of an eyelet portion 10, which is riveted through the rear wall of the envelope at the line of overlap and of the laterally extending fingers or prongs 11 which are adapted to be bent upwardly from the envelope and to be bent backwardly again, is applied to the back wall 2. In addition, the flap is here shown as provided with an aperture 12 forming the eyelet to receive the prongs or fingers 11 of the fastener, and this eyelet is here shown as reinforced in well known manner by means of patches 13 applied to the opposite faces of the flap and surrounding the aperture 12. The crease 14 on which the envelope flap is adapted to be folded over against the back wall of the envelope is formed exactly midway between the center of the fastener eyelet 10 and the center of the aperture 12, so that when the flap is folded upon this crease line, the aperture 12 and fastener will register and therefore the prongs 11 may be bent upwardly and passed through the aperture 12 without distorting the flap or the envelope. So far as the finished product is concerned, it has the same appearance as an envelope finished under the old method, pro-

vided the latter is carried out accurately. It will be apparent that if the crease line 14 is formed previous to the attachment of the fastener and the formation of the aperture 12, and if this crease line should happen to be nearer the center of the fastener 9 than the center of the aperture 12 by one-sixteenth of an inch for instance, then when the flap was folded on this crease line the aperture 12 and the fastener will be out of register in this instance one-eighth of an inch because when the flap is folded over the error is multiplied by two. That is to say, if the crease line 14 is nearer the center of the fastener 9 by one-sixteenth of an inch, it is so also one-sixteenth of an inch farther from the center of the aperture 12, so that the inaccuracy of registry between these parts becomes one-eighth of an inch. In the present method the crease line 14 is in all cases exactly midway between the center of the fastener 9 and the center of the aperture 12 at the point 15 so that when the flap is folded the aperture 12 and the fastener 9 always register with each other and it is therefore unnecessary to distort the flap or the envelope in order to close the attachment, and it is unnecessary to form a new crease line for the purpose.

In Figures 1 and 2 I have shown parts of a machine for attaching the fasteners to the envelope and reference may be had to the U. S. patent to W. Richardson dated Dec. 3, 1918, and numbered 1,286,413, for the illustration of the complete machine for performing this operation. In the drawings herein I have shown the tube 16 which carries the arm 17 extending at right angles to the tube 16 and it is provided on its outer end with a raised portion 18 which forms an anvil by means of which the eyelet of the fastener is adapted to be upset or riveted. There is a plunger 19 guided in a tubular support 20 and the forward end of this plunger is adapted to co-operate with the anvil 18 to upset the rivet in the operation of attaching the fastener to the envelope. Generally, the anvil arm 17 is stationary, whereas the plunger 19 moves in relation to it. The support 16 which carries the anvil arm forms a guide for a plunger 21 which is adapted to apply one of the patches or reinforcement pieces 13 to the eyelet in the flap of the envelope. There is another tubular support 22 arranged in axial alignment with the support 16 and there is a plunger 23 sliding in this support, and it serves to apply one of the patches 13 to the opposite side of the flap to the one applied by the plunger 21. The parts just described are all common to at least one known form of attaching machine.

In addition to the parts described, I have added a stationary male creasing member 24 shown in Figures 1 and 2, and it is of suffi-

cient length to form the crease across the flap of the widest envelope the machine is adapted to handle. I have shown this creasing member supported at top and bottom 5 upon bars 25, 26 which are connected by the end frames 27 to form a rigid rectangular support. This creasing member is provided with a slot 28 through which the anvil arm 17 extends so that the forward edge 29 of 10 this creasing member is continuous; and in the preferred construction this forward edge is made with a V shape as shown in the drawings, in order to constitute the male member of the creasing device. There is another creasing member 30 mounted parallel 15 with the member 24 and also supported on the upper and lower rods 25, 26 but this member is adapted to slide on these bars or rods toward and from the stationary member 24. In order to provide for moving this 20 creasing member, I have shown a toggle lever arrangement in Figure 1. There are short brackets 31 secured in fixed positions respectively to the upper and lower bars 25, 25 26 behind the movable creasing member 30. At the point 32 there is pivoted to this bracket a lever arm 33 and these two lever arms come together near the vertical center 30 of the creasing device and are provided at their overlapping ends with longitudinal 35 slots 34 in which engages a driving pin 35. This pin is guided in a horizontal slot 36 in the tubular support 22 and it is moved simultaneously with and by the plunger 23 which may be operated by the mechanism 40 shown in said patent. Attached to each lever arm 33 by a pivotal connection 37 is a connecting link 38 and the opposite ends of these are pivoted at 39 to the movable creasing member 30. As the plunger 23 is moved to the left in Figures 1 and 2, the pin 35 acts upon the overlapping ends of the levers 33 and these levers, pivoting at the points 32 act through the links 38 to move the 45 creaser bar 30 to the left; and upon a reverse movement of the plunger 22 the levers 33 are reversed in movement and the creaser bar 30 is moved to the right in the drawing. Usually the plunger 23 moves about one inch 50 in extent and the movement is reduced through the levers 33 so that the creaser bar 30 need only move about three-eighths of an inch. These proportions are merely stated to indicate one desirable form of device 55 which may be used in carrying out my method. The forward or active edge of the creaser bar 30 is provided with a V shape crotch 40 which co-operates with the edge 29 of the other creaser bar, so that these two 60 edges compress the envelope material between them for the purpose of forming the crease 14.

In carrying out my method, the envelope is applied to the machine in the manner shown in Figure 2, by placing the flap 5

between the plungers 21, 23, with the portion of the anvil arm 17 which protrudes through the creasing bar 24 inserted within the open end of the envelope until the corners 8 come up against the edge 29 of the male creaser 70 member, this being the method of gauging the position of the envelope in relation to the attaching device. In this position, the anvil 18 faces the rear wall of the envelope at the inside thereof, and the plunger 19 is in line 75 with the anvil. The active edges of the creasing bars in Figure 2 are exactly halfway between the axial lines of the plunger 19 and anvil 18 and the axial line of the plungers 21, 23. Preferably the envelope 80 contacts with the stationary plunger 21, with the creasing edge of the male member 24 and with the anvil 18. It will be understood that one of the metal fasteners is threaded onto the projecting end of the plunger 19 85 and that each plunger 21, 23 is supplied with a strip of patch material suitably supplied with adhesive, all of which may be as shown in said patent. As the machine is set into operation to apply the fastener and the 90 patches, the following actions take place: The plunger 19 carrying the metal fastener approaches the anvil 18 presenting the cylindrical portion of the fastener through the rear wall 2 of the envelope, until the inner 95 end of this cylindrical portion of the fastener strikes the anvil; and a continuation of the movement causes the same to be upset or riveted against the inner surface of the back wall 2 so that when the plunger 19 has completed its movement, the fastener 100 will have been attached to the envelope. While this movement is taking place, the plunger 23 is also moving to the left in Figures 1 and 2, so that a patch 13 is applied by 105 both plungers 21, 23 to the intermediate flap and surrounding the opening 12. In some cases the aperture 12 may be formed by an interior punch at the time the patches are pressed against the wall of the flap. When 110 the plunger 23 moves to the left in the operation just described, the creaser bar 30 is also moved to the left, so that at the moment the plunger 19 and the plunger 23 complete their movements, the wall of the envelope is 115 compressed between the edges 29, 40 of the creasing members, so that the crease 14 is formed while the envelope is held by the plunger 19 by the anvil 18 and the plungers 21, 23. As a result of this the crease 14 is 120 certain to be positioned exactly midway between the center of the eyelet and the center of the metal fastener, at least at the point 15 in Figure 4. After the attaching and 125 creasing operations have been completed, the plungers and the female creaser are retracted and the envelope withdrawn ready for the operation to be repeated with another envelope.

By forming the crease simultaneously with 130

the application of the fastener or of the eyelet, but preferably simultaneously with both of these operations, it is possible to position the crease with such accuracy that when the flap is folded on this crease the eyelet and fastener will always register. The operation is so dependable that it is unnecessary to inspect or examine the product for the position of the crease line as this is always accurately positioned under my method. It will be understood that other mechanism than that described herein may be used in carrying out the method, the principle of which resides in the formation of the flap crease simultaneously with the attachment of the fastener or the eyelet, or with both of these operations, or at least while the envelope is held at the fastener and eyelet.

Having described my invention, what I claim is:

1. A method of the character described which consists of applying fastening means to an envelope having a flap, and in forming

a crease on which the flap is adapted to be folded, simultaneously with the attachment of the fastening means to the envelope.

2. A method of the class described which consists of applying closing means to one wall and to the flap of an envelope, and in forming a crease on which the flap is adapted to be folded, while the flap and envelope are engaged by means passing through the wall of the envelope and said flap.

3. A method of the class described which consists of applying a fastener to the wall of an envelope, simultaneously applying eyelet means to the flap of the envelope, and simultaneously therewith forming a crease on which the flap is adapted to be folded, said crease being disposed midway between the center of said fastening means and the center of said eyelet means.

Signed this 10th day of June, 1926, at the city, county and State of New York.

JAY G. SWAB.
